UNITED STATES PATENT OFFICE.

JOSEPH D. MORGAN, OF ODIN, ILLINOIS.

STRAW AND HAY STACKER.

SPECIFICATION forming part of Letters Patent No. 248,777, dated October 25, 1881.

Application filed July 6, 1881. (No model.)

To all whom it may concern:

Be it known that I, JOSEPH D. MORGAN, of Odin, in the county of Marion, and in the State of Illinois, have invented certain new and useful Improvements in Straw and Hay Stackers; and I do hereby declare that the following is a full, clear, and exact description thereof, reference being had to the accompanying drawings, and to the letters of reference marked thereon, making a part of this specification.

This invention relates to certain improvements in hay or straw stackers, and it has for its object to provide a means whereby the hay or straw may be elevated and dumped at any desired place, as more fully hereinafter specified. This object I attain by the apparatus illustrated in the accompanying drawings, in which—

Figure 1 represents a perspective view of my improved apparatus, and Fig. 2 a detached view of a portion of the apparatus.

The letter A indicates a derrick mounted upon a suitable base, B. The said derrick is made in two parts, the upper part being adjustable 25 or extensible in suitable ways, C, in such manner that the device may be adapted to various heights. The horizontal arm of the derrick is pivoted in the ordinary manner, so that it can be swung around to dump the load at any desired point.

The letter D indicates a series of pulleys over which passes a cord or rope, M, to one end of which is secured a bail, N, carrying the hay-fork P, which is pivoted between the ends 35 of the bail and adapted to swing therein. The handle of the fork is slotted, as indicated by the letter R, and is adapted to receive the end of a rod, S, loosely attached to the bail at T.

The letter U indicates a latch pivoted in a 40 horizontal slot, V, in the handle of the fork, which latch is adapted to engage the rod S and hold the fork in a horizontal position.

W indicates a cord attached to the latch, by means of which it may be moved to release the latch and dump the load.

The latch U is formed of a strong wire bent so as to form a pivotal eye, a, through which a fulcrum-pin, b, passes. A hook, c, is also formed on one end of the latch, and an eye, d, is formed on the opposite end thereof. The hook c passes through the slotted end of the fork-handle, and through an eye, e, formed on the end of the rod S. A latch thus formed of a single wire may be made by any farmer having ordinary mechanical skill, and is not liable to break or to casually disengage the rod S from the fork-handle while elevating a load, as the hooked portion c is supported on opposite sides of the slot R when it is engaged with the eye on rod S.

The pulley at the head of the derrick is mounted in a block, Y, swiveled in the derrick, so as to turn as the horizontal arm of the derrick swings around.

The operation of my invention will be readily understood from the foregoing without further description.

Having thus fully described my invention, what I claim, and desire to secure by Letters Patent, is—

The combination of the bail pivoted to the fork-head, the eye formed thereon, the rod S, looped to said eye, and provided with an eye, e, on its opposite end, and a latch, U, formed with the parts a c d, the part c serving as the attachment for the rod S to the slotted end of the fork-handle, substantially as described.

In testimony whereof I affix my signature in presence of two witnesses this 28th day of June, 1881.

JOSEPH D. MORGAN.
